UNITED STATES PATENT OFFICE.

OSCAR H. ELIEL, OF LA SALLE, ILLINOIS.

HERMETIC SEAL.

Application filed May 9, 1921. Serial No. 467,960.

To all whom it may concern:

Be it known that I, OSCAR H. ELIEL, a citizen of the United States, and a resident of the city of La Salle, in the county of 5 La Salle and State of Illinois, have invented certain new and useful Improvements in a Hermetic Seal; and I do hereby declare that the following is a full, clear, and exact description of the same, reference being had 10 to the accompanying drawings, and to the numerals of reference marked thereon, which form a part of this specification.

This invention relates to a hermetic seal, and particularly to an improved means for 15 hermetically sealing burial caskets to prevent the transmission of fluid between the interior thereof and the surrounding medium.

In hermetically sealing burial caskets it 20 is desirable that means be provided whereby a tight seal may be quickly and economically accomplished with simple equipment such as is ordinarily available and at the same time it is desirable that it be possible 25 to conveniently inspect the line of sealing connection between the upper and lower portions of the casket. Caskets which are best adapted to be hermetically sealed are constructed of stamped metal and in providing 30 an economical and durable construction it is necessary that the steps in the stamping process be reduced to a minimum and that undue tensioning of the metal be avoided.

It is an object therefore of the present invention to provide a hermetic seal for metal 35 burial caskets wherein a fusible sealing material is secured to adjacent portions of the casket by the process of sweating or by a similar method of indirect application of 40 heat to the sealing material.

It is another object of this invention to 45 provide a hermetic seal wherein adjacent portions of a container having strips of fusible material interposed therebetween are subsequently secured thereto both by the direct and the indirect application of heat.

It is a further object of this invention 50 to provide a hermetic seal which may be conveniently inspected.

It is an important object of this invention to provide an economical, easily applied, hermetic seal for burial caskets.

Other and further important objects of 55 this invention will be apparent from the

disclosures in the specification and the accompanying drawings.

The invention (in a preferred form) is shown on the drawings and hereinafter more fully described.

On the drawings, Figure 1 is a transverse vertical section through a perspective view of a burial casket employing the improved hermetic seal of this invention.

Figure 2 is an enlarged detail section 60 showing the method of joining the bottom and top portions of the casket together by the hermetic seal.

Figure 3 is a view similar to Figure 2 showing a slightly modified form of hermetic seal.

Figure 4 is a view similar to Figure 2 showing another form of hermetic seal.

Figure 5 is a view similar to Figure 2 showing a slightly modified form of hermetic seal.

Figure 6 is a view similar to Figure 5 showing another form.

As shown on the drawings, the hermetic seal of this invention is particularly adapted for use in connection with a metal casket and for purposes of illustration a stamped metal burial casket is shown and described herein. Said casket comprises a bottom or body portion 1 which is provided with integral vertical side walls and end portions 2, and integral with said walls and end portions is an outwardly extending substantially horizontal flange 3. An integral horizontal flange 4 of a cover portion 5 is adapted 80 to rest on said flange 3 and the fusible sealing material is interposed and sealed between the flanges 3 and 4 in a manner which will now be described.

In the construction shown in Figure 2 the flange 3 is provided with an integral peripheral flange 6 which extends upwardly therefrom slightly above the top of the flange 4 on the cover 5. Interposed between the flanges 3 and 4 and between the outer edge of the flange 4 and the inner wall of the flange 6 is a strip of fusible sealing material 7 which is adapted to effect a hermetic seal between the cover 5 and the body of the casket.

In the construction shown in Figure 3, the flange 4 is also provided with an upwardly extending integral peripheral flange which is represented by the reference numeral 8 and which acts to secure a strip of fusible

material similar to the strip 7 in position to effect a seal between the cover and the body of the casket.

In the construction shown in Figure 4, 5 the flange 8 is replaced by an outwardly inclined flange 9 whereby the fusible sealing material 7 is more securely locked in position.

In the construction shown in Figure 5, 10 the flange 4 is provided with a downwardly extending peripheral flange 10 which rests on the upper side of the flange 3 and the seal is effected by means of fusible material 11 which is interposed between said 15 flange 10 and the inner side of the flange 6.

In the construction shown in Figure 6 the peripheral flanges on the flanges 3 and 4 are omitted and the seal is effected by the interposition of a strip of fusible material 20 12 therebetween.

In order that the fusible material which is interposed between the flanges 3 and 4 and the retaining flanges associated therewith may be fused to effect a hermetic seal 25 between the cover of the casket and the body portion thereof, it is of course necessary that heat be applied thereto. This is preferably accomplished by applying a soldering iron or other suitable heat applying means to the outside of the flange 4 or the flange 3 and by thus applying heat the fusible material and the flanges will be secured together by a process which is known in the art as sweating. While this 30 sweating process in itself assures a very effective seal between the flanges, the seal may be further insured by applying heat to the exposed edge of the fusible material as for example between the outer edge of the 35 flange 4 and the inner wall of the flange 6 in Figure 2. This may be conveniently accomplished by applying a soldering iron to the edge of the fusible material and drawing the iron entirely around the periphery 40 45 of the casket while in contact with this exposed edge. When this is done an external inspection will readily show that the casket is actually sealed.

It is of course understood that fusible 50 sealing material may be interposed between certain portions in unfused condition and subsequently fused by pouring in additional sealing material in a molten state, or the

parts may be sealed together by first properly positioning the same and subsequently 55 pouring the fused sealing material therebetween.

In effecting the seal a fusible material comprising a lead alloy such as solder is 60 preferably employed but it is of course understood that any suitable fusible sealing material may be employed without departing from the spirit of this invention.

It will be noted that this seal is particularly adapted for use in connection with 65 stamped metal caskets, since the same is effected without the provision of any channels in the metal and consequently the undesirable tensioning of the metal to form these channels is eliminated. On account of the 70 ease with which the seal may be applied and the simple equipment by which it may be fused into sealing relation, it is of course evident that it is particularly adapted for 75 use in connection with burial caskets and it is also apparent that the seal of this invention may also be used to advantage in connection with the hermetic sealing of other metal containers.

I am aware that numerous details of construction may be varied through a wide range without departing from the principles of this invention, and I therefore do not purpose limiting the patent granted otherwise than necessitated by the prior 80 art.

I claim as my invention:

A hermetic seal for burial caskets comprising an outwardly extending horizontal flange on the body portion, a cover portion 90 having an upturned edge adapted to overlap said flange, an upturned edge on said horizontal flange, the upturned edge of the cover portion lying within the upturned edge on said horizontal flange and spaced away 95 therefrom, and fusible material sealingly secured between said flange and its upturned edge and the margin and upturned edge of the cover portion.

In testimony whereof I have hereunto 100 subscribed my name in the presence of two subscribing witnesses.

OSCAR H. ELIEL.
